UNITED STATES PATENT OFFICE.

CHARLES D. BLAKE, OF GLENS FALLS, NEW YORK.

SAWMILL-HEAD-BLOCK CLEANER.

Application filed September 28, 1923. Serial No. 665,294.

To all whom it may concern:

Be it known that I, CHARLES D. BLAKE, a citizen of the United States, residing at Glens Falls, in the county of Warren and State of New York, have invented certain new and useful Improvements in Sawmill-Head-Block Cleaners, of which the following is a specification.

This invention relates to an improvement which is adapted to be used in association with a saw-mill head block.

It is my object to provide an improvement for a device of this class which may be accurately defined as a cleaner attachment for saw-mill head blocks, the title being descriptive of the function which the device serves to perform.

It is also my object to provide a device of this class which comprises an exceedingly simple and inexpensive blade for scraping dust accumulations from the groove of the so-called knee, the device being characteristic in that it can be used in conjunction with conventional head blocks without requiring extensive alteration thereof.

Other objects will appear as the nature of the invention is better understood and the same consists in the novel form, combination and arrangement of parts herein-after more fully described, shown in the accompanying drawing and claimed.

In the drawing, wherein like reference characters indicate corresponding parts throughout the several views.

Figure 1 is a side elevational view of a base plate and work seating knee forming part of a conventional form of saw mill head block now in use, the base plate being provided with a scraping knife in accordance with the present invention.

Figure 2 is a top plan view, partly broken away of the base plate shown in Figure 1 and drawn on a larger scale, and

Figure 3 is an enlarged perspective view of the scraping blade or knife detached.

Referring more in detail to the drawing, 5 indicates a base plate of a saw mill head block upon the upper end of which is slidably mounted a work feeding knee or block 6 of well known form, said knee or block being moved toward the right of Figure 1 in a well known manner for feeding the work to the saw. The work feeding knee or block 6 is shown in its rearmost position.

The present invention as before stated includes means for automatically scraping

the groove of the knee 6 during the operation of the latter, so that said knee will continue to operate indefinitely in an efficient manner, and whereby rendering of the saw mill inoperative for cleaning of the knees is made unnecessary. I obtain this object by attaching a scraping blade 8 to the base plate 5, so that the scraping edge 9 of said blade is exposed at the upper edge 65 of the base plate 5 for scraping the groove of the knee 6 and thereby keeping the latter clean and smooth as is necessary to prevent sluggish operation of said knee.

In the preferred construction of the invention, the scraping blade 8 consists of a relatively long flat lower portion adapted to be seated within a groove provided as indicated generally at 10, in one side of the base plate 5, said blade further including 70 a laterally directed and twisted relatively short upper end portion seated in a deepened upper end portion of the groove 10, as indicated at 11 so that the upper edge 9 of the blade is disposed obliquely of the 75 upper edge of the base plate 5 and extends from side to side of the latter and side to side of the knee 6. The preferred manner of mounting the blade 8 consists in providing the same with longitudinally elongated 80 slots 12 through which are passed the screws 13 that are threaded into the base plate 5 by means of which the blade 8 may be vertically adjusted so that the edge 9 is exposed to the proper degree above the upper 85 edge of the base plate 5, and by means of which the blade 8 is maintained effectively 90 in said adjusted position.

In operation, with the blade 8 located slidably behind the point 7 which forms 95 the rearmost point at which the inner end of the knee moves, the blade 9 will extend into the groove of the knee 6 as the latter is moved longitudinally toward the right of Figure 1, for feeding the work to the 100 saws and as said knee is moved back to starting position toward the left for feeding another piece of work to the saws. This results in keeping the groove of the knee perfectly clean and smooth at all times and 105 results in operation of the knee with a minimum frictional resistance.

From the above description, it is believed that the construction and operation as well as the advantages of the invention will be 110 readily understood and appreciated by those skilled in the art.

Minor changes may be made without departing from the spirit and scope of the invention as claimed.

What I claim as new is:

- 5 1. An improvement in saw mill head block cleaners comprising a conventional base plate, and a work feeding knee slide-
able along the upper face of the base plate; said improvement consisting of forming a
10 transverse diagonal groove in the base plate, said groove extending entirely across the upper face of the base plate, a scraper plate lying in said groove and twisted laterally at its upper end to extend diagonally across and in contact with the ad-
15 jacent face of said knee, and means ad-

justably and removably securing said plate in the groove.

2. A cleaner attachment for a conventional saw-mill head block, said attachment comprising a plate provided with longitudinally spaced elongated slots, the lower portion of said plate being relatively long and flat to provide an attaching portion to be connected to one flat side of said block, the upper end thereof being twisted laterally with its free upper edge cut diagonally whereby to extend diagonally across the top of said block.

In testimony whereof I affix my signature.

CHARLES D. BLAKE.
